UNITED STATES PATENT OFFICE

148,544

DESIGN FOR A CAMERA

Morris Kaplowitz, Brooklyn, N. Y., assignor to
Federal Manufacturing & Engineering Corp., a
corporation of New York

Application December 21, 1946, Serial No. 135,667

Term of patent 14 years

(Cl. D61—1)

To all whom it may concern:

Be it known that I, Morris Kaplowitz, a citizen of the United States, residing in the city of New York, Borough of Brooklyn, in the county of Kings and State of New York, have invented a new, original, and ornamental Design for a Camera, of which the following is a specification, reference being had to the accompanying drawing, constituting a part thereof.

Fig. 1 is a perspective view of a camera showing my new design. For convenience of illustration, the carrying strap is shown fragmentarily in solid lines, and completed in broken lines to indicate that the same has a conventional length;

Fig. 2 is a top view thereof. For convenience of illustration, the carrying strap is shown fragmentarily in this and the following views;

Fig. 3 is a front elevational view; and

Fig. 4 is a rear elevational view of the same.

The dominant features of my design reside in the outline and configuration of the camera,

which comprises a substantially flat body having a slightly convexially curved rear surface and a frontal extension consisting of a part of a cylinder extending for a portion of the width of said body carrying a lens-holding cylinder of smaller diameter than said first mentioned cylinder and being axially perpendicular thereto, all as shown.

I claim:

The ornamental design for a camera, substantially as shown and described.

MORRIS KAPLOWITZ.
